BACK WASHER

William Dixon, Henderson, Ky.

Application November 22, 1943, Serial No. 511,325

8 Claims. (Cl. 4—184)

This invention is a device for use in facilitating the washing of the back while bathing, and an object of the invention is to provide a portable device of this character which is well adapted for the purpose designed.

The invention together with its objects and advantages will be best understood from a study of the following description taken in connection with the accompanying drawings wherein—

Figure 1 is a side elevational view illustrating the application of the invention.

Figure 2 is a perspective view of the device.

Figure 3 is a sectional view through a soap receptacle, and

Figure 4 is a detail view partly in section and partly in elevation illustrating a drive and clutch mechanism hereinafter more fully referred to.

Referring to the drawings by reference numerals it will be seen that in the preferred embodiment thereof the device comprises a support in the form of a pair of laterally spaced parallel base rods 5—5 which adjacent one end are connected together and secured in spaced relation through the medium of a cross bar 6. At the ends thereof the bars 5 are provided with opening 7 which through the medium of screws or other suitable fastening elements the base bars may be secured to a floor or the like for anchoring the device more or less permanently.

Rising from the base bars 5 are standards 8 that are braced with respect to the base bars 5 through the medium of brace rods 9.

At the upper ends thereof the standards 8 are connected by a cross bar 10.

Depending from the cross bar 10 and secured at their upper ends to the bar 10 in any suitable manner as by being integral therewith are elongated bearing bars 11 that are braced relative to the standards 8 through the medium of brace bars 12.

A shaft 13 is supported between the upper ends of the bearing bars 11, the ends of the shaft 13 extending through openings provided therefor in the bars 11 and having their terminals journaled in the upper ends of the standards 8. Mounted on the shaft 13 to turn therewith is a roller 14 over which is trained an endless scrubbing-towel 15 which is also trained over a roller 16 which is rotatably supported between the bearing rods 11 at the lower ends of the rods as clearly shown in Figure 2.

Suitably mounted on one of the standards 8 adjacent the upper end of the latter, is a gear case 17 into which one end of the roller shaft 13

extends. On said end thereof shaft 13 is equipped with a gear 18 that is in mesh with a worm 19 on one end of the shaft 20 of an electric motor 21. Motor 21 is supported through the medium of a suitable bracket structure 22 provided therefor adjacent the upper end of one of the brace bars 9. It will thus be seen that drive from motor 21 is transmitted through the gearing 19 and 18 to the roller shaft 13 whereby to cause the endless towel 15 to move over the rollers 14 and 16.

Further in accordance with the present invention there is provided a receptacle 23 for liquid soap and the receptacle 23 has the bottom thereof perforated as at 24 and as shown in Figure 3. The receptacle 24 is mounted on the end of a supporting arm 25 which latter at its free end is provided with a hook 26 that engages over the cross bar 10 in a manner shown. Threadedly engaged with the hook-equipped end 26 of the supporting arm or bracket 25 is a thumb screw 27 that is adapted to be threaded home into binding engagement with the bar 10 for securing the bracket 25 at the desired position of adjustment lengthwise of the cross bar 10.

Suitably mounted in the receptacle 23 is an agitator 28 as shown in Figure 3 and the shaft of the agitator 28 is suitably connected with a flexible shaft 29.

Shaft 29 has an end thereof extending into the gear case 17 and on said end is provided with a clutch element 31 that is complementary to a clutch element 32 provided on the worm-equipped end of motor shaft 20 as also shown in Figure 4.

For moving the clutch 31 into and out of engagement with the clutch element 32 there is provided a clutch shifting fork 33 pivotally mounted on a bracket 35 provided therefor on the gear case 17. (See Figure 4). It will thus be seen that when it is desired to transmit drive from the motor to the agitator 28 for revolving the latter fork 33 is shifted in a proper direction to engage clutch element 31 with clutch element 32.

As clearly suggested in Figure 1, in actual practice, the support is positioned adjacent one end of a bath tub 36 with the standards 8 disposed at opposite sides of the tub and the lower portion of the towel 15 extending down into the tub. In this connection it will be noted that the bearing bars 11 are spaced inwardly from the standards 8 a distance sufficient to accommodate the side walls of the tub.

In using the device to wash the back the user, as suggested in Figure 1, sits in the tub with the back in contact with the towel 15 so that obviously the towel in its path of travel contacts the back

in a manner to briskly rub the same. When desired to supply soap to the back for the washing of the same the receptacle 23 is brought into use and obviously the contents of the receptacle discharging through the perforations 24 will fall upon the back of the person. In order that the contents in a good, soapy condition will be supplied to the back, the agitator 28 may be employed and to bring the agitator 28 into play the lever 33 is thrown in a manner to engage the clutch elements 31, 32 so that drive will be transmitted from the motor and through the flexible shaft 29 to the agitator 28.

It will thus be seen that with this device the back of the bather may be conveniently thoroughly scrubbed and cleaned.

It is thought that a clear understanding of the construction, utility and advantages of a device of this character will be had without a more detailed description.

Having thus described the invention what is claimed as new is:

1. In a device of the character described, a supporting structure adapted to be arranged adjacent one end of a bath tub and embodying a pair of vertical parallel bearing-rods, upper and lower rollers respectively rotatably supported between and by the upper and lower ends of said rods, and an endless towel trained over said rollers to engage the back of a bather sitting upright within the bath tub.

2. In a device of the character described, a supporting structure adapted to be arranged adjacent one end of a bath tub and embodying a pair of vertical parallel bearing-rods, upper and lower rollers respectively rotatably supported between and by the upper and lower ends of said rods, and an endless towel trained over said rollers to engage the back of a bather sitting upright within the bath tub, a soap dispensing receptacle mounted on said supporting means and arranged relative to said towel for discharging soap downwardly onto the back of the bather in contact with the towel.

3. In a device of the character described, a supporting structure adapted to be arranged adjacent one end of a bath tub and embodying a pair of vertical parallel bearing-rods, upper and lower rollers respectively rotatably supported between and by the upper and lower ends of said rods, and an endless towel trained over said rollers to engage the back of a bather sitting upright within the bath tub, a soap dispensing receptacle mounted on said supporting means and arranged relative to said towel for discharging soap downwardly onto the back of the bather in contact with the towel, a motor mounted on the supporting structure, and driving mechanism between said motor and one of said rollers.

4. In a device of the character described, a supporting structure adapted to be arranged adjacent one end of a bath tub and embodying a pair of vertical parallel bearing-rods, upper and lower rollers rotatably supported between said rods, and an endless towel trained over said rollers, a soap dispensing receptacle mounted on said supporting means and arranged relative to

5 said towel for dispensing soap on the back of a bather in contact with the towel, and driving mechanism connected with one of said rollers, and an agitator arranged in said soap dispensing receptacle and means operatively connecting said agitator with said driving mechanism.

5. In a device of the character described, a portable supporting structure, vertically spaced upper and lower horizontal rollers rotatably mounted on said supporting structure in the same vertical plane, an endless towel trained over said rollers, a bracket arm extending forwardly from and adjustable laterally of said supporting structure above the upper roller, interengaging means 10 on said arm and supporting structure for securing said arm at the desired position of lateral adjustment on said supporting structure, and a soap dispensing receptacle mounted on said arm.

15 6. In a device of the character described, a portable supporting structure, vertically spaced upper and lower horizontal rollers rotatably mounted on said supporting structure in the same vertical plane, an endless towel trained over said rollers, a bracket arm extending forwardly from and adjustable laterally of said supporting structure above the upper roller, interengaging means 20 on said arm and supporting structure for securing said arm at the desired position of lateral adjustment on said supporting structure, a soap dispensing receptacle mounted on said arm, an electric motor mounted on said supporting structure, and drive means operatively connecting said motor with one of said rollers.

25 7. In a device of the character described, a portable supporting structure, vertically spaced upper and lower horizontal rollers rotatably mounted on said supporting structure, an endless towel trained over said rollers, a bracket arm extending forwardly from said supporting structure above the upper roller, interengaging means 30 on said arm and supporting structure for securing said arm at the desired position of lateral adjustment on said supporting structure, 35 and a soap dispensing receptacle mounted on said arm, an electric motor mounted on said supporting structure, and drive means operatively connecting said motor with one of said rollers.

40 8. In a device of the character described, a portable supporting structure, vertically spaced upper and lower horizontal rollers rotatably mounted on said supporting structure, an endless towel trained over said rollers, a bracket arm extending forwardly from said supporting structure above the upper roller, interengaging means 45 on said arm and supporting structure for securing said arm at the desired position of lateral adjustment on said supporting structure, and a soap dispensing receptacle mounted on said arm, an electric motor mounted on said supporting structure, and drive means operatively connecting said motor with one of said rollers, an agitator arranged within said soap dispensing receptacle, and power transmitting means 50 operatively connecting said motor with said agitator and including a flexible shaft and a clutch device for controlling the transmission of drive from the shaft of said motor to said flexible shaft.

55 9. In a device of the character described, a supporting structure adapted to rest upon the floor and constructed to straddle a bath tub adjacent one end of the latter, a vertical scrubbing device suspended from the supporting structure and arranged to depend into the bath tub in position to engage the back of a bather sitting upright within the latter, said scrubbing device including an endless towel, and means to 60 cause traveling movement of said endless towel.

65 WILLIAM DIXON.
